(57) **CLAIM**

The ornamental design for a dual spout bottle, as shown and described.

DESCRIPTION

FIG. 1 is a perspective view of a dual spout bottle showing the design;

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof;

FIG. 8 is a perspective view of the dual spout bottle with its straw spout extended; and,

FIG. 9 is a left side view thereof.

1 Claim, 5 Drawing Sheets
